UNITED STATES PATENT OFFICE

104,939

DESIGN FOR A CONTAINER FOR MECHANICAL PENCIL FILLERS

Paul S. Hauton, Atlanta, Ga.

Application April 26, 1937, Serial No. 68,975

Term of patent 14 years

To all whom it may concern:

Be it known that I, Paul S. Hauton, a citizen of the United States, residing at #423 Houston Street, Atlanta, county of Fulton, State of Georgia, have invented a new, original, and ornamental Design for a Container for Mechanical Pencil Fillers, of which the following is a specification, reference being had to the accompanying drawing, forming part thereof.

In the drawing:

Fig. 1 is a front elevation of a container for mechanical pencil fillers showing my new design, and

Fig. 2 is an end view of my new design.

I claim:

The ornamental design for a container for mechanical pencil fillers as shown.

PAUL S. HAUTON.
